UNITED STATES PATENT OFFICE.

ULYSSES S. STEWART, OF BALTIMORE, MARYLAND, ASSIGNOR OF ONE-HALF TO EDGAR C. STEWART, OF BALTIMORE, MARYLAND.

SECTIONAL BIN.

Application filed November 3, 1922. Serial No. 593,726.

To all whom it may concern:

Be it known that ULYSSES S. STEWART, a citizen of the United States, residing at Baltimore, in the State of Maryland, has invented certain new and useful Improvements in Sectional Bins, of which the following is a specification.

This invention relates to improvements in sectional knock-down bins.

10 One object of the invention is to provide an improved sectional structure for knock-down bins whereby the walls of the bin may be quickly assembled and locked together by means which are permanently attached 15 to the walls themselves, and which will be of such construction as to be rigidly braced against either internal or external pressure.

Another object of the invention is to provide an improved construction of sectional bin in which the sections may be assembled one on top of another, and locked together against lateral displacement, so that the height of the bins may be readily increased or decreased as the contents are supplied 25 thereto or removed therefrom.

With these, and other objects in view, the invention is illustrated in the accompanying drawing, wherein,—

Fig. 1. shows the improved bin in perspective.

Fig. 2. illustrates a vertical sectional detail through one corner of the bin as the same would appear if viewed on the line 2—2 of Fig. 1.

35 Fig. 3. shows in perspective, an interior corner view of the bin.

Fig. 4. illustrates, in perspective, an exterior corner view of the bin, wherein two sections only are employed.

40 Fig. 5. shows in perspective the corner construction of adjacent walls but separated one from the other, and

Fig. 6. illustrates a vertical sectional detail through the cover and front wall as the 45 same would appear if cut on the line 6—6 of Fig. 1.

Referring to the drawing, the numeral 7, 50 designates an end wall of one section and 8, a side wall of the same section. These walls are of uniform height and thickness so that their upper and lower edges will become flush when the two are brought together.

In the present instance each side wall 8, carries an angle-iron 9, on its outer side 55 which is rigidly secured thereto and which

has a right-angle bend 10, that extends across the vertical edge 11, of said side wall and projects horizontally for a purpose that will presently be explained.

Each end wall 7, of a section is provided with a hook plate 12, which is secured on the upper edge of said wall and projects laterally beyond the vertical end 13, thereof, and each hook plate is provided with a down-turned hook 14, which is spaced from but is parallel to said vertical end 13, as shown in Fig. 5, of the drawing.

In the present instance the upper corner of each side wall 8 is provided with a corner notch 15, also as shown in Fig. 5, of the drawing, but this notch is not essential, and may be omitted.

It is thus to be understood that each end of a side wall 8, is provided with an angle-iron 9, and each end of an end wall 7, is provided with a hook plate 12, with a down-turned hook 14, thereon.

On the interior, each side wall 8, is provided with a vertically-extending batten 16, which is set back slightly away from the vertical edge 11. This batten is also spaced from the bend 10, of the angle iron 9, which the outer side of the side wall 8 carries, as can be clearly seen in Fig. 5, of the drawing.

Each end wall 7, also has a batten 17, at 85 each end thereof and these battens have one vertical edge flush with the vertical edge 13, of the said end wall.

By referring to Figs. 2, 3 and 5 of the drawing it will be noted that on the sections above the lowermost section, the interior corner battens 16 and 17, have their lower ends projecting downwardly below the horizontally bottom edges of the side and end walls to which they are connected respectively, and that these lower projecting ends extend down below the top edges of the side and end walls respectively beneath them so that an upper section is locked against lateral displacement by its battens engaging the 95 sections beneath it.

The lowermost section also has interior corner battens 18 and 19, but these battens do not project below the lower or bottom edge of this lowermost section, as can be seen 105 in Figs. 2 and 3, of the drawing.

A fastening device, such as a hasp 20 and staple 21, is provided on the lowermost or foundation section whereby to rigidly lock the lower side and end walls together on the 110

inside, a wedge pin 29 with a wire 30 therein being passed through the staple 21 to hold the hasp engaged with the staple and thus keep said lowermost walls in positions at 5 right angles with respect to each other.

Each end wall 7, is preferably provided with an eye or loop plate 21, as shown in Figs. 1-4 and 6, of the drawing for a purpose that will presently be explained.

10 In setting up the bin, the lowermost side walls 8 and end walls 7, are brought together so that the ends 10, of the angle irons 9, will overlap the vertical outer face 11 of the side wall 8, while the edge 23 of the batten 19 on the inner side of the end wall 7, will project in front of the vertical edge 24, of the batten 18 on the side wall, as seen in Fig. 3, of the drawing. The down-turned hooks 14, projecting from the upper horizontal edge of the end walls 7, are also fitted over the end or notched portion 15, of the side wall so that both side and end walls of this lowermost section are thereby locked against either inward or outward movement. 20 The hasp 20, and staple 21, are then brought into locking engagement on the inside corner battens and secured by the pin 29 and wire 30, and the lowermost section, comprising two vertical side walls and two vertical end walls, is rigidly held in an upright position.

A second section may then be set up on top of the lower section, in precisely the same manner as was the lower section, the only difference being that the battens 16 and 17, on the superposed section will have their lower ends projecting downwardly below the top edge of the section beneath it, whereby to hold said superposed section 35 against lateral displacement.

If a third, fourth or more sections are desired to gain the desired height, the operations of superposing said sections are simply repeated.

40 The question of providing a bottom for the bin is one that is immaterial to the invention, but it preferably is desirable to provide a top or cover, whether the bin be one, two, three or more sections in height.

45 In the present instance I provide a cover 25, whose under side has crosswise battens 26, secured thereto. These battens are spaced from the end edges 27, of the cover, a distance equal to the thickness of the end

walls 7, as seen in Figs. 2 and 6 of the drawings.

The battens 26, of the cover are also slightly shorter than the interior width of the bin between the side walls 8, so that when the cover is laid on the uppermost section, the battens will snugly fit inside of the end and side walls and be held against lateral movement. I also provide the opposite ends of the cover with hasps 28, which are secured on the under side to the battens and project from the cover so as to swing down over the eye or loop plates 21, on the end walls 7, of the uppermost section, so that pad-locks may be placed through the eyes and securely lock the cover in place.

Having described my invention, I claim,—

1. A sectional knock-down bin comprising a plurality of superposed sections each section having separable end and side walls and each end wall having means at each end thereof for exteriorly engaging the side walls and each side wall having exterior means at each end thereof for engaging the end walls, and means on the interior and at each end of each end and side wall of a section for interiorly bracing said section walls the interior means on one section extending down and engaging the walls of the section beneath it.

2. A sectional knock-down bin comprising a lower section having side and end walls; exterior means on both ends of each wall for exteriorly engaging the other wall of said lower section; interior battens on both ends of each wall of said lower section which battens lap when the walls are brought together; locking means on said interior battens to lock the said lower section walls together on the interior; a superposed section on said lower section said superposed section also having side and end walls that are exteriorly locked together and interior battens on both ends of the superposed section walls to interiorly lock the same together and these latter battens on the superposed section extending from the superposed section walls down at the inner side of the walls of the lower section whereby to lock the superposed section against lateral movement with respect to the lower section.

100 In testimony whereof I affix my signature.

ULYSSES S. STEWART.
